UNITED STATES PATENT OFFICE

149,919

DESIGN FOR A BOW TIE HOLDER

Louise L. Ullmann, New York, N. Y.

Application November 21, 1946, Serial No. 134,977

Term of patent 3½ years

(Cl. D80—9)

To all whom it may concern:

Be it known that I, Louise L. Ullmann, a citizen of the United States and a resident of the city, county, and State of New York, have invented a new, original, and ornamental Design for a Bow Tie Holder, of which the following is a specification, reference being had to the accompanying drawings, forming part thereof, in which:

Fig. 2 is a side view thereof; and,

Fig. 3 is a front end view.

I claim:

The ornamental design for a bow tie holder, substantially as shown.

LOUISE L. ULLMANN.
